2,414,678

GARMENT

Edward Waxman, University City, Mo., assignor
to G. & R. Manufacturing Company, St. Louis,
Mo., a corporation of Missouri

Application January 25, 1945, Serial No. 574,501

2 Claims. (Cl. 2—73)

1

This invention relates generally to improvements in women's garments, and more particularly to an undergarment commonly referred to as a slip.

An object of the invention is to provide a garment of the kind referred to, which may be readily drawn on and off over the head of the wearer, and which is constructed in such a manner that it will be form fitting in the bodice portion, and free draping in the skirt portion, without sagging.

Another object of the invention is to provide a slip construction in which the matching panels are each cut on the bias, but assembled in such manner so that the adjacent panels will be alternately biased, thereby providing matching edges that support the stitches in a manner to provide a balanced pull on the seams, thereby providing a stronger seam, and also thereby preventing sagging of the several sections composing the finished garment.

Another object of the invention is to provide a garment of the kind mentioned, which may be economically manufactured with a minimum yardage wastage, but which will be attractive in appearance, and durable in use.

Additional advantages of the invention will be apparent from the following detailed description taken in connection with the accompanying drawing, in which:

Fig. 1 is a front view of the garment disclosing the preferred embodiment of the invention in a woman's slip;

Fig. 2 is a back view;

Fig. 3 is an enlarged section, taken substantially on the line 3—3 of Fig. 1;

Fig. 4 is an enlarged section, taken substantially on the line 4—4 of Fig. 1; and

Fig. 5 is an enlarged section, taken substantially on the line 5—5 of Fig. 1.

The garment, as illustrated in the drawing, includes a skirt section A and a bodice section B, and may be constructed from any suitable woven material.

The skirt section includes panels 10 and 11 that flare slightly downwardly from the waist line at their outer edges. These panels are cut on the bias but, in cutting and assembling them, the material is arranged in such a manner that the bias of the panels 10 and 11 alternate. The two panels 10 and 11 have their inner edges substantially vertical, but with their outer edges slightly inwardly inclined upwardly and are joined together with a central seam 12.

The back of the skirt section is formed from duplicate panels 13 and 14 similar in form and

shape to the front panels 10 and 11, and are likewise cut on the bias, but with the bias extending in alternate directions. The panels 13 and 14 have their adjacent interior substantially vertical edges joined by a seam 15. The outer edge of panel 10 is secured to the slightly inwardly upwardly inclined outer edge of the panel 13, and the panel 11 is similarly secured to the panel 14 by side seams 16 and 17, respectively.

10 The arrangement of the panels is such that, when the skirt section is completed, each alternately disposed panel is biased in the opposite direction. The stitching entering the oppositely biased material forms a strong seam. Thus it will be observed that the skirt section forms a truncated conical section comprised of substantially similar segments, but each having an alternately biased arrangement of the material. The skirt section is thereby constructed in such a manner that the tension and pull at all of the seams securing the panels together will be balanced, resulting in a stronger seam, and also sagging of the skirt is minimized.

15 The balanced arrangement of the panels in respect to the bias of the material likewise has the effect of preventing the skirt portion from unduly contracting longitudinally over the knees of the wearer in sitting position, and tends to prevent creeping of the front section of the skirt, and thereby to preserve the lower hem of the skirt in circumferential alignment, whether the wearer is standing or sitting.

20 It will be understood that the skirt section, formed from the panels thus described, has a uniform drape free from sagging and durably secured at the seams.

25 The lower end of the skirt is finished in the usual manner by a hem 18.

The bodice portion of the garment is formed 30 from a single thickness midriff panel 19 cut on the bias, affording circumferential stretch and contraction. The panel 19 has a straight lower edge, an annular central portion that develops into a duplicate convex upper edge, forming a 35 V-shaped extension. The panel 19 is connected at its lower edge to the top edges of the panels 10 and 11 by a seam 20.

40 The bodice section of the garment at the back is completed by substantially rectangular double thickness panels 21 and 22, the overlying panels being similarly biased, but the panels being oppositely biased with respect to each other.

45 The seaming that secures the lower panel 19 to the upper edge of the skirt portion is continued 50 across the waist line and secures the panels 21

and 22 to the panels 13 and 14, respectively, and the central seam 23, in vertical alignment with the seam 15, extends up to the top line of the garment which is slightly convex, and top stitched at 24.

The front section of the bodice is completed by double thickness panels 25 and 26 cut on the opposite bias of the piece goods, and cut to form a lower edge that meets respectively the angular upper line of the panel 19 to which they are secured by a seam 27. The lower edge of each of the panels 25 and 26 are darted and Shirred, in order to form in each an outwardly extending flare constituting breast pockets or cups that are form fitting.

The upper edge of the panels 25 and 26, respectively, are angular in shape, the apex of which angles are approximately at the center of each of the panels 25 and 26.

Shoulder straps 28 are secured thereto, and extend over the shoulder portion, and are connected to the center of the back line of the panels 21 and 22 of the back section, respectively. The inner edges of the panels 25 and 26 are finished with a finished or closed seam 29, and a strap 30 connects them at the upper edge.

The panels 25 and 26 are preferably of double thickness, and are similarly biased in respect of the two thicknesses thereof, but oppositely biased in respect of each other.

A garment constructed, as described, forms in effect a combination slip and a brassière in which the bodice portion of the garment forms a bust support, which, because of the arrangement of the panels in biased relationship, together with the circumferential contraction of the midriff sec-

tion, forms a highly satisfactory bust support, that effects the desired uplift when worn.

It will be seen, therefore, that the garment fully accomplishes the intended purpose thereof. I do not limit myself to the exact construction shown and described, except as expressed in the following claims.

What is claimed is:

1. A garment of woven material, comprising a skirt portion consisting of similarly shaped panels arranged with a pair at the front of the skirt and a pair at the rear of the skirt, each of said panels being oppositely biased and joined by side seams and by seams centrally disposed in respect of the front and back of said skirt; a midriff front panel secured to the top of the skirt section and being cut on the bias to expand and contract; a pair of breast panels secured to said midriff panel; and a rear bodice member including oppositely biased sections joined by a central seam connected to the side edges of said bust panels, and said midriff panel.

2. A garment of woven material comprising a skirt portion consisting of panels arranged with a pair at the front of the skirt and a pair at the rear of the skirt, each of said panels being oppositely biased and joined by side seams and by a seam at the matching edges of the panel in the front and in the rear; a midriff front panel secured to the top of the skirt section and being cut on the bias to expand and contract; a pair of breast panels secured to said midriff panels; and a rear bodice member connected to the side edges of the bust panels and to said midriff panel.

EDWARD WAXEMAN.
